ATTORNEY

UNITED STATES PATENT OFFICE.

DANIEL JOHNSON, OF ASHLAND, OHIO.

IMPROVEMENT IN FORCE-PUMPS.

Specification forming part of Letters Patent No. **177,401**, dated May 16, 1876; application filed May 5, 1876.

To all whom it may concern:

Be it known that I, DANIEL JOHNSON, of Ashland, in the county of Ashland, and State of Ohio, have invented certain new and useful Improvements in Force-Pumps, of which the following is a specification:

My invention relates to force-pumps; and it consists in the construction and arrangement of the device for preventing the same from freezing, as will be hereinafter more fully set forth.

In order to enable others skilled in the art to which my invention appertains to make and use the same, I will now proceed to describe its construction and operation, referring to the annexed drawing, which forms a part of this specification, and in which—

Figure 1 is a front view, Fig. 2 is a vertical section, and Fig. 3 is a section through the air-chamber and valve.

A represents the pump cylinder, with piston or plunger B constructed in the usual manner for force-pumps. The plunger-rod c extends up to and above ground, where it is connected with a lever-handle for operating the plunger.

The pump-cylinder A communicates with a box, E, by a short connecting-pipe, a, said box being held to the frame surrounding the pump-cylinder by any suitable means. To the box E is connected the air-chamber G, constructed substantially in the form shown, or in any other suitable or convenient shape. From the box E extends the discharge-pipe H, the lower end of which is below the entrance-pipe a to said box. The discharge-pipe H extends up above the ground, and is constructed in any suitable manner. Within this pipe at a suitable point is placed a valve, d, said valve being provided with an upwardly-projecting stem, i, which enters the lower end of

a pipe, I, within the discharge-pipe. The upper end of pipe I is curved outward and passes through the side of the discharge-pipe, as shown. This point on the discharge-pipe should be below the point of frost.

The normal position of the valve d is on the seat b, closing the discharge-pipe at that point. Now, as the pump is worked and the water forced up the discharge-pipe H, the valve d is raised until it closes the lower end of the interior pipe I, and the water can pass freely around the same and up the discharge-pipe.

As soon as the motion of the pump is stopped the valve d, of its own weight, aided by the column of water above it, will at once fall down on the seat b, preventing the water above the same from passing down. This water, however, will at once pass into and out through the pipe I.

It will thus be seen that when the pump is in operation the vent-pipe I is closed by the valve, and as soon as the pump is stopped said pipe is opened, discharging the water above it, and hence making the pump non-freezing.

Having thus fully described my invention, what I claim as new, and desire to secure by Letters Patent, is—

In combination with the discharge-pipe H of a force-pump, the valve-seat b, interior vent-pipe I, and valve d, with stem i, substantially as and for the purposes herein set forth.

In testimony that I claim the foregoing as my own, I affix my signature in presence of two witnesses.

DANIEL JOHNSON.
